CHILD'S CAR SEAT

Hyman Wener, 482 94th Ave., Chomedey,
Laval, Quebec, Canada

Filed Aug. 9, 1974, Ser. No. 496,055

Term of patent 7 years

Int. Cl. D6—01

U.S. Cl. D6—9

FIG. 1 is a view in side elevation of a child's car seat showing my design; and

FIG. 2 is a side view of FIG. 1.

The side of the seat not shown is a mirror image of the side shown while the rear is plain and unornamented.

I claim:

The ornamental design for a child's car seat, as shown and described.
